UNITED STATES PATENT OFFICE

2,577,447

AUTOGRAPHIC REGISTER

Maxel L. Bright, Berkeley, Calif., assignor to
 Moore Business Forms, Inc., Emeryville, Calif.,
 a corporation of Delaware

Application July 7, 1950, Serial No. 172,578

4 Claims. (Cl. 282—22)

1

This invention relates to improvements in record devices, more particularly to autographic registers of the portable type having a supply compartment for a supply of record sheets or record units, preferably including a plurality of record and transfer or carbon sheets bound together in transfer relation, and held in the supply compartment whereby they may be removed one after another and transferred into writing position.

It is a general object of the invention to provide in a record device of the type mentioned, improved means for holding or binding a supply of separate record sheets or record units in position in the supply compartment so that the units may be transferred one after another into writing position on a writing platen or the like, and held and supported in writing position by the holding or binding means during inscription, after which the inscribed units can be easily detached from the binding means by a simple manual operation.

Another and more particular object of the invention is to provide in a record device of the class mentioned, an improved binding arrangement for binding the record sheets or record units both in the record supply compartment and in writing position on the writing platen, the binding means being provided with releasing means permitting the inscribed units to be quickly and easily detached.

According to another feature of improvement of the invention, binding posts or pins are provided for holding the record units in position in a supply compartment and arranged in a novel manner to permit the units to be transferred one at a time into writing position on a writing platen while still retained by the binding posts which are provided with yielding retaining means, such as a spring plate or the like, enabling the units to be quickly and easily detached after inscription thereof.

Another object of the invention is to mount the binding pins or posts for the record units in a novel manner in proximity to an exit opening through which the units may extend into writing position on the platen which is preferably movably mounted to expose the record supply compartment.

A further object of the invention is to provide in a record device of the class mentioned, an improved mounting means for mounting the binding pins or posts for the record units whereby the binding pins may be retracted by manual operation so as to expose them for installation of a new supply of record units.

2

Other objects of the invention will be in part pointed out in connection with the following detailed disclosure of an illustrative but preferred embodiment of the invention, and will be in part obvious as the disclosure proceeds.

The invention accordingly comprises the features of construction, combination of elements, and arrangement of parts, which will be exemplified in the construction hereinafter set forth and the scope of the application of which will be indicated in the claims.

For a more complete disclosure of the nature, objects and advantages of the invention, reference is had to the following detailed description of the illustrative embodiment, and to the accompanying drawings in which:

Fig. 1 is a top perspective view of a portable autographic register embodying the invention;

Fig. 2 is a perspective view similar to Fig. 1 in which the register is turned end for end;

Fig. 3 is an enlarged vertical longitudinal section taken approximately on line 3—3 of Fig. 2 looking in the direction of the arrows, parts being shown in elevation;

Fig. 4 is a fragmentary horizontal section and plan view, the section being taken approximately on the line 4—4 of Fig. 3;

Fig. 5 is a horizontal section like that of Fig. 4, the parts being shown in a different operative position;

Fig. 6 is a vertical transverse section taken approximately on the line 6—6 of Fig. 3 looking in the direction of the arrows, parts being shown in elevation and parts being broken away for clearness of disclosure;

Fig. 7 is a transverse vertical section approximately on the line 7—7 of Fig. 1 looking in the direction of the arrows; and

Fig. 8 is a perspective, partially diagrammatical view of a record unit especially convenient for use in the improved autographic register.

Referring to the drawing for a detailed description of the illustrative embodiment of the invention, a casing indicated generally at 10 provides a support for the operative elements of the register and provides a housing for a supply S of record units A, a typical one of which is shown in Fig. 8. The casing 10 may be constructed of any suitable sheet material such as metal, plastic, or the like, and includes a bottom 11, side walls 12, and upper end sections 13 and 14. These casing walls provide a space or compartment in which the supply of record units is supported or housed and a writing platen 15 overlies the supply compartment, forming a cover and

being hinged to the side wall 12 by means of a longitudinally disposed hinge 16 connected to a down-turned marginal flange extending to one longitudinal edge portion of the platen. At its opposite longitudinal edge, the platen 15 is provided with a down-turned longitudinal flange 17 telescoping within the adjacent casing side wall 12. These down-turned longitudinal flanges reinforce and stiffen the platen, and the flange 17 forms a holding device for holding the platen in normal closed position and cooperates with a spring latch 18 engaging in a depression in the flange. The flat writing surface of the platen 15 is depressed slightly below the upper horizontal surface of the casing, as best shown in Fig. 7, providing a firm flat surface in which the record unit being inscribed is supported and held steady in writing position.

Positioned within the support or casing near the forward end thereof is a supporting or binding device for the record supply including upright binding posts 19 adapted to enter apertures in the forward ends of the record units for holding the record supply in position on the casing or support. The binding device for the record units is positioned at the forward end of the casing beneath the top end plate 14 and includes a frame plate 20 having upper and lower supporting flanges 21 engaging the inner surfaces of the upper and lower casing walls. The frame plate 20 of the binding device is firmly secured in position within the casing by means of mounting screws 22 engaging the forward end plate of the casing and threaded into supporting lugs 23 welded or otherwise firmly attached to the frame plate.

Mounted for longitudinal movement within the casing and supported by the frame plate 20, is a supporting carriage 24 to which the binding posts 19 are firmly attached for movement therewith as best shown in Figs 3, 4 and 5. This supporting carriage has a lower plate 25 slidably engaging the lower casing wall, and a forwardly disposed upper plate 26 substantially parallel with the lower plate 25, and extending between the upper and lower carriage plates is a vertical plate 27. Horizontal tubular supports and guides 28 are firmly attached to the frame plate 20 and extend rearwardly thereof. Each of the tubular supports 28 telescopically receives a guide rod 29 firmly attached at its outer end to the vertical plate 27 of the supporting carriage, thus providing a supporting and guiding means for the supporting carriage.

An actuator or actuator plate 30 is positioned just beneath the upper plate 26 of the supporting carriage, being attached or integral at its forward edge to a supporting plate 31 which is mounted for transverse sliding movement on the rear side of the frame plate 20. The supporting plate 31 is attached to the frame plate 20 by means of an attaching member or bar 32 connected at its inner end as by riveting or welding to the supporting plate 31 and extending outwardly through the frame plate in an elongated transverse slot 33. The attaching bar 32 is continued outside of the elongated slot 33 into an opening or transversely elongated slot in the forward end of the casing to form an operating handle 34 for manual control of the binding device as later more fully described. A retaining washer or collar is secured on the attaching bar 32 at the outside of the frame plate 20. Thus the actuator plate 30 may be reciprocated transversely by means of the handle 34.

Mounted upon the upper side of the actuator plate 30 are two cam rollers 36 respectively engaging in inclined cam slots 37 in the upper carriage plate 26 which are inclined to the axis of longitudinal movement of the supporting carriage 24. Opposite end portions of these cam slots are formed with divergent pockets 38 in which the cam rollers 36 rest at extremities of movement of the carriage in either direction. A spring latch in the form of a spring plate 39 is attached at one extremity at 39' to the lower surface of the actuator plate 30 having a latch lug 40 at its opposite extremity extending through an aperture in the actuator plate and slidably engaging with the adjacent surface of the upper carriage plate 26. When the carriage reaches its extreme retracted position, the latch lug 40 automatically engages by spring pressure in the latch opening 41 in the plate 26 thus holding the carriage in its retracted position. The latch lug 40 is rounded at its engaging part so as to be disengaged by application of pressure on the operating parts.

As best seen in Fig. 3, a retaining spring plate 42 is attached to the upper flange 21 of the frame plate 20 extending transversely of the register and contacting with the upper end portions of the binding posts 19 so as to retain the record units in bound position, but being yieldably retractable slightly from engagement with the posts to permit a record unit to be detached from the binding posts. It will be noted that the binding posts in their retracted operative position as shown in Fig. 3 are positioned adjacent to the forward end of the platen and substantially beneath the top casing plate 14. Due to the fact that the platen 15 is depressed slightly below the top plate 14, an exit opening 43 is provided adjacent to the forward edge of the platen 15 through which the record units when bound on the binding posts 19 may extend into position upon the platen in which they are supported for receiving inscriptions by means of a pencil or otherwise. Hence with this novel arrangement the record units are supported by means of the binding posts both in the record supply pack and in writing position upon the platen.

Although the record units A may be of various forms such as single record sheets or assemblies 50 of record sheets attached together, the improved record device is especially useful for record units A such as shown in Fig. 8. This record unit A embodies a plurality of record sheets A' with carbon sheets C interleaved in transfer relation therewith, all being bound together in a binding stub A². Record units of this type are fully described in patent No. 2,120,161 Stevens, dated June 7, 1938. Apertures A³ are formed in the record units for receiving the binding posts 19. 55 When this record unit A is inscribed upon the platen 15, the inscriptions are transferred by the carbon sheets to the underlying record sheets after which the record sheets may be readily detached from the assembly along the weakened 60 severance lines A⁴.

An illustrative embodiment of the invention having been fully described, the operation thereof will be obvious, and may be summarized as follows. When the supply pack S of record units 70 are installed in the register on the binding posts 19 and it is desired to make an inscription on one of these units, the combined cover and platen 15 is swung into open position on its hinge 16 and the top record unit A raised from the supply pack after which the platen is closed in its normal 75

writing position and the top unit A is placed in writing position upon the platen as shown in Figs. 1, 3 and 7. When in this position, it will be noted that the top record unit still remains attached to the binding posts 19, extending therefrom through the exit opening 43 into writing position upon the platen. After the inscriptions have been entered, the inscribed record unit is raised manually somewhat and an upward and rearward pull exerted thereon thus causing the resilient holding means or spring plate 42 to yield slightly and to move away from the end portions of the binding posts 19 sufficiently to permit the record unit to slide over the tops of the posts and thus be released and removed from the register. The inscribed record leaves may then be selectively separated from the rest of the record unit as above indicated and described in the Stevens patent referred to. The record units may be thus inscribed one after another until the supply is exhausted.

When it is desired to install a new supply of record units, the platen 15 is swung into open position and the supporting carriage 24 together with the binding posts is moved rearwardly from beneath the upper cover plate 14 and the retaining spring plate 42, whereby the posts are in accessible position so that a fresh supply pack may be installed thereon; this is the position as shown in Fig. 5. To retract the supporting carriage as described, the operator engages the handle 34 moving it laterally from the position shown in Fig. 4 to that shown in Fig. 5, thus moving the actuator plate 30 laterally and causing the cam rollers 36 to engage the inclined cam slots 37 thus moving the carriage and binding posts 19 into their retracted accessible position. After the new supply has been installed, the reverse movement of the handle 34 causes the carriage and pins to be moved into their normal operative position as shown in Figs. 3 and 4. When in this final position, the latch lug 40 mounted at the free end of the latch spring 39 is yieldingly urged into latching position in the latching aperture 41 thus yieldingly retaining the carriage together with the supply pack in normal operative position.

Since certain changes may be made in the above construction and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. In a record device, in combination, a rigid supporting casing having a space therein for containing a supply of record units, a platen, means movably supporting said platen with respect to said casing above said supply space and with its head end at a predetermined minimum distance from the corresponding end of the casing when in operative position, binding means including a binding post carried by said casing and normally positioned slightly beyond the head end of said platen when the latter is in said operative position, said binding post being accessible both above and below said platen to bind both the units in the supply space and a unit resting in writing position on the platen, said binding means further including a yielding retaining element fixed to the casing adjacent the head end thereof and normally resiliently en-

gaging the free end of said binding post to releasably retain said units upon the post, a carriage supporting the binding post and slidably with respect to said casing, guiding means on the casing for confining the movement of said carriage solely to longitudinal movements with respect to the casing, and means for manually moving said carriage away from and toward said head end of the casing to alternately free said post from said fixed yielding retaining element and bring it into engagement therewith.

2. In a record device, in combination, a rigid supporting casing having a space therein for containing a supply of record units, a platen, means movably supporting said platen with respect to said casing above said supply space and with its head end at a predetermined minimum distance from the corresponding end of the casing when in operative position, binding means including a binding post carried by said casing and normally positioned slightly beyond the head end of said platen when the latter is in said operative position, said binding post being accessible both above and below said platen to bind both the units in the supply space and a unit resting in writing position on the platen, said binding means further including a yielding retaining element fixed to the casing adjacent the head end thereof and normally resiliently engag- 15 ing the free end of said binding post to releasably retain said units upon the post, a carriage supporting the binding post and slidably with respect to said casing, guiding means on the casing for confining the movement of said carriage solely to longitudinal movements with respect to the casing, and means for manually moving said carriage away from and toward said head end of the casing to alternately free said post from said fixed yielding retaining element and bring it into engagement therewith.

20

3. In a record device, in combination, a rigid supporting casing having a space therein for containing a supply of record units, a platen, means movably supporting said platen with respect to said casing above said supply space and with its head end at a predetermined minimum distance from the corresponding end of the casing when in operative position, binding means including a binding post carried by said casing and normally positioned slightly beyond the head end of said platen when the latter is in said operative position, said binding post being accessible both above and below said platen to bind both the units in the supply space and a unit resting in writing position on the platen, said binding means further including a yielding retaining element fixed to the casing adjacent the head end thereof and normally resiliently engag- 25 ing the free end of said binding post to releasably retain said units upon the post, a carriage supporting the binding post and slidably with respect to said casing, guiding means on the casing for confining the movement of said carriage solely to longitudinal movements with respect to the casing, and means for manually moving said carriage away from and toward said head end of the casing to alternately free said post from said fixed yielding retaining element and bring it into engagement therewith.

30

4. In a record device, in combination, a rigid supporting casing having a space therein for containing a supply of record units, a platen, means movably supporting said platen with respect to said casing above said supply space and with its head end at a predetermined minimum distance from the corresponding end of the casing when in operative position, binding means including a binding post carried by said casing and normally positioned slightly beyond the head end of said platen when the latter is in said operative position, said binding post being accessible both above and below said platen to bind both the units in the supply space and a unit resting in writing position on the platen, said binding means further including a yielding retaining element fixed to the casing adjacent the head end thereof and normally resiliently engag- 35 ing the free end of said binding post to releasably retain said units upon the post, a carriage supporting the binding post and slidably with respect to said casing, guiding means on the casing for confining the movement of said carriage solely to longitudinal movements with respect to the casing, and means for manually moving said carriage away from and toward said head end of the casing to alternately free said post from said fixed yielding retaining element and bring it into engagement therewith.

40

5. In a record device, in combination, a rigid supporting casing comprising a bottom plate, side and end walls, and a short top wall portion extending from one of the end walls, all providing a supply space for record units, a movable platen adapted to substantially complement said top wall portion to cover the supply space in said casing, a gap between the head edge of said platen and the adjacent edge of the top wall portion providing a narrow exit passage for record units, non-clamping binding means for said units carried by said casing and including a binding post positioned normally slightly beyond the head edge of said platen and serving to bind both the units in the supply space and a unit resting in writing position on the platen, said last named unit extending through said exit passage, record unit retaining means comprising a spring plate carried by said short top wall portion and normally resiliently engaging the free end of said binding post to releasably retain the units upon the post,

45

6. In a record device, in combination, a rigid supporting casing comprising a bottom plate, side and end walls, and a short top wall portion extending from one of the end walls, all providing a supply space for record units, a movable platen adapted to substantially complement said top wall portion to cover the supply space in said casing, a gap between the head edge of said platen and the adjacent edge of the top wall portion providing a narrow exit passage for record units, non-clamping binding means for said units carried by said casing and including a binding post positioned normally slightly beyond the head edge of said platen and serving to bind both the units in the supply space and a unit resting in writing position on the platen, said last named unit extending through said exit passage, record unit retaining means comprising a spring plate carried by said short top wall portion and normally resiliently engaging the free end of said binding post to releasably retain the units upon the post, a slid- 50 able element disposed within said casing and supporting said binding post, guiding means on the casing for confining the movement of said element solely to the longitudinal direction with respect to the casing, means for manually moving said element away from the head end of the casing to free said post from said fixed yielding retaining element for unimpeded application of a new supply of record units thereto.

7. In a record device, in combination, a rigid supporting casing comprising a bottom plate, side and end

walls, and a short top wall portion extending from one of the end walls, all providing a supply space for record units, a movable platen hinged along one side edge to one of said side walls and adapted to substantially complement said top wall portion to cover the supply space in said casing, said platen being depressed slightly below the plane of said top wall portion, a gap between the head edge of said platen and the adjacent edge of the top wall portion providing a narrow exit 10 passage of fixed dimensions for record units, non-clamping binding means for said units carried by said casing and including a binding post positioned normally slightly beyond the head edge of said platen and serving to bind both the units 15 in the supply space and a unit resting in writing position on the platen, said last named unit extending through said exit passage, record unit retaining means comprising a spring plate carried by said short top wall portion and normally resiliently engaging the free end of said binding post to releasably retain the units upon the post, a slideable element disposed within said casing 20 and supporting said binding post, guiding means

on the casing for confining the movement of said element solely to the longitudinal direction with respect to the casing, means for manually moving said element away from the head end of the casing to free said post from said fixed yielding retaining element for unimpeded application of a new supply of record units thereto.
